SPRING ANCHOR AND PIVOT PIN LOCK

Thomas D. Mantle, Normandy, Mo., assignor to
Carter Carburetor Corporation, St. Louis, Mo.,
a corporation of Delaware

Application January 30, 1950, Serial No. 141,298

1 Claim. (Cl. 308—2)

1

This invention relates to pivotal supports for levers and consists particularly in a novel combination biasing spring and pivot pin locking device.

The type of automotive fuel pump now generally in use has a reciprocating diaphragm actuated by a pivoted lever held yieldingly in engagement with a cam rotated by the engine so as to intermittently actuate the pumping diaphragm in the charging direction and release the diaphragm for yielding actuation in the discharge direction by a compression spring bearing against the diaphragm. The operating lever is customarily held in engagement with the cam by a coiled spring which bears against the lever at one side of the pivotal supporting pin. Various means have been provided for locking the pin in position. However, I have found that this object may be accomplished more simply and less expensively than heretofore by forming an integral extension on the lever biasing spring which embraces an annular recess on the pin, and thus holds both the spring and pin in position.

Accordingly, the main object of the present invention is to provide novel means, as in a pump of the above type, for simplifying and decreasing the cost of the means for anchoring a pivoting lever and its supporting pin.

This object and other more detailed objects hereafter appearing are attained by the structure illustrated in the accompanying drawing in which:

Fig. 1 is a side view and section illustrating an automotive fuel pump embodying the invention;

Fig. 2 is an enlarged detail showing the operating lever, its pivotal support, and the lever biasing spring;

Fig. 3 is a side view of the lever biasing spring disassembled;

Fig. 4 is an end view of the lever biasing spring;

Fig. 5 is a view of the pivotal pin disassembled.

The fuel pump in Fig. 1 comprises a body 10 including the fuel connections, fuel valves, and various dome structures which do not constitute the present invention. A right angle housing 11 extends from the fuel pump body and has a flange 12 at its inner end for attachment to the engine (not shown). Clamped between housing 11 and the fuel pump body is a diaphragm 13 having a stem 14 secured centrally thereto by means of large washers 15 and 16. Pump operating lever 17, of inverted U section, is pivotally supported in housing 11 upon a pin 18 journalled in bearing bosses 19 formed in the legs of the lever. The lever extends inwardly beyond housing 11 for engagement with the operating cam (not shown)

2

and, at its opposite end, underlies a pad 20 on stem 14 for one-way actuation of the stem in the direction to move diaphragm 13 in the charging direction. A coiled spring 21 is compressed between a shoulder 22 in housing 11 and upper cup washer 16 on the diaphragm for urging the diaphragm in the pump discharge direction. The space around stem 14 within shoulder 22 is sealed by a flexible diaphragm 23.

10 Lever 17 is constantly urged in the clockwise direction, for causing its free, inner end to bear against the operating cam, by means of a coiled compression spring 25 which has a seat 26 in the interior of the housing and bears eccentrically against the under surface of lever 17. The upper end coil of spring 25, which engages the lever, is extended, as at 27, in approximate S shape and has a hook 28 embracing an annular recess 29 in pin 18. The sides of the recess constitute longitudinal shoulders cooperating with hook 28 to maintain the pin and spring 25 properly aligned. Thus, lateral displacement and play between the lever and pivot pin are resisted, while extension 27 also serves to stabilize the sealing of spring 25 15 against lever 17.

20 25 The details of the fuel pump are not essential and may be modified in various ways. These and other modifications as occur to those skilled in the art may be made without departing from the spirit of the invention and the exclusive use of all modifications as come within the scope of the appended claim is contemplated.

I claim:

30 35 The combination of a pivoting lever with a journal bearing, a pivotal pin journalled in said bearing and having an annular recess, and a coiled compression spring projecting laterally from said lever and with an end coil axially bearing against and biasing said lever, the wire of said end coil being extended to and embracing said pin at said 40 recess so as to resist relative lateral displacement of said lever and said pin while stabilizing the relationship of said spring and said lever.
